Atty.

UNITED STATES PATENT OFFICE.

CHARLES H. MILLER, OF MINNEAPOLIS, MINNESOTA.

STREET-INDICATOR FOR CARS.

SPECIFICATION forming part of Letters Patent No. 358,467, dated March 1, 1887.

Application filed October 8, 1886. Serial No. 215,669. (No model.)

To all whom it may concern:

Be it known that I, CHARLES H. MILLER, of Minneapolis, county of Hennepin, and State of Minnesota, have invented certain new and 5 useful Improvements in Street-Indicators for Cars, of which the following is a specification.

My invention relates to an improvement in a device adapted for use in street-cars to indicate the name or number of the streets that 10 the car passes, for the convenience of the passengers; and the invention consists, generally, in an indicator having a belt or ribbon bearing the names of the streets mounted on cylinders or rolls actuated by an intermittently- 15 revolving mechanism, by which each name is brought to view in succession, and which is capable of being reversed at the will of the operator, in order that the names may be correctly shown as the car passes back and forth 20 over the line.

In the drawings which form part of this specification, Figure 1 is an end elevation of my improvement, showing the operating mechanism. Fig. 2 is a front elevation of the same.

25 2 represents the frame or casing of the register, which supports the shafts 3 of the cylinders or rolls 4, and is provided with an opening, 5, on its face, through which the name of the street is shown. This opening is preferably covered by a glass plate to protect the mechanism in the casing. The shafts 3 extend 30 through the ends of the casing and are mounted in suitable bearings therein. The mode of attachment which I have shown and which I prefer is to form slots 7 in each end of the case 35 at the proper distance apart for the rolls, and extending from one edge of the end to the center or to the point of location of the shaft. By this means I am enabled to readily insert or 40 remove the rolls. A stop, 9, may be placed in the slot back of the shaft, and secured to the case to hold the said shaft in place.

The cylinders or rolls 4 are secured to the shaft by suitable means and located between 45 the bearings. The shafts at one end project beyond the bearings. The upper shaft is provided with a spur-pinion, 11, and the lower shaft with a spur-pinion, 13, substantially of the same size. An idler-gear, 15, revolves 50 upon a stud fastened in the end of the casing, and is arranged to mesh with the pinion 11.

17 is a plate secured to the casing by a pivot, 19. This plate carries a stud, 20, upon which a spur-gear, 21, revolves. This gear is of substantially the same size as the idler 15, and is 55 so located with reference to the other gears that it may be brought into mesh with either the pinion 13 or the idler-gear 15 by moving the plate 17 upon its pivot. The plate 17 may be operated to effect this result by any convenient means. That which I employ is as follows:

The plate 17 extends beyond the circumference of the gear, and its extremity is slotted to receive the eccentric 23, which turns upon 60 a pin, 24, secured to the casing. A handle, 25, upon the eccentric provides means for operating it. When the throw of the eccentric is down, the plate 17 is in its lowest position and the gear 21 engages the pinion 13. When 65 the throw of the eccentric is up, the plate is in its highest position and the gear 21 engages the idler 15. Stops may be placed upon the end of the casing at the limit of the movement of the plate, in order that the eccentric may 70 bind at the two extremes of its motion and prevent it from being accidentally turned.

26 is an alarm-bell located upon the plate 17, and arranged to be struck by a spring-hammer, 28. The arm of this hammer comes 75 in contact with the teeth of the gear 21, and as the gear revolves the hammer strikes the bell.

27 is a ratchet attached to and concentric with the gear 21, preferably cast in one piece therewith.

85 29 is a lever, preferably fulcrumed upon the pivot-bolt 19, and provided with a spring-pawl, 30, adapted to engage the ratchet 27. A spring, 31, is attached to this lever and to the casing, for the purpose of raising the said lever 90 to its original position after it has been forced down to operate the ratchet. The end of the lever preferably extends through the end of the car to be within convenient reach of the driver or conductor, and may, if required, be 95 provided with a cord or depending rod and handle.

33 is a ribbon of paper or other suitable material wound upon the rolls 4, one end being attached to the upper and the opposite end attached to the lower of said rolls. This ribbon 100 has printed upon it at proper intervals the

names of the streets to be indicated. The spacing of the names upon the ribbon must be in relative proportion to the travel of the circumference of the cylinders or rolls 4, and the length may be varied to suit the number of names required.

35 are friction-springs on the inside of the end casing and bearing against the end of each roll to give them the proper tension to keep 10 the ribbon straight.

The operation is as follows: The ribbon, which has been properly printed to correspond with the streets to be indicated, is placed in the casing, and at starting will be wound upon 15 one of the rolls and properly adjusted to bring the name of the first street opposite the opening in the casing. For convenience in the description, it will be considered that it is wound upon the top roll. The train of gears will

20 then be in the position shown in Fig. 1. As a street is passed the lever 29 is forced down, and the pawl 30 engages the ratchet and partially revolves it and the gear 21, connected thereto. This in turn gives a partial revolution to the 25 pinion 13 and the shaft and cylinder connected therewith, thus drawing the ribbon onto the lower roll and unwinding it from the other, and showing the name of the next street at the opening 5. As this operation of the lever is 30 performed the bell-hammer, actuated by the gear teeth, strikes the bell and draws attention to the fact that the change has been made. This operation is repeated upon leaving each street until the terminus of the road is reached.

35 The eccentric 23 is now turned so as to bring

the gear 21 into engagement with the idler 15, thus reversing the motion of the ribbon by the same operation of the lever. On the return trip the same operation is carried out, except that the ribbon is wound upon the opposite roll and the streets will be indicated in the reverse order.

What I claim is—

1. The combination, in a street-indicator, with the rolls provided with the gears 11 and 13 and the indicating-ribbon, of the idler 15, meshing with the gear 11, the pivoted plate 17, the gear 21, mounted on said plate and adapted to be moved to engage with either of said gears 11 or 13, the ratchet, the operating lever, and the eccentric 23, engaging said plate 17, and adapted to move it and lock it in engagement with either of said gears, substantially as described.

2. The combination, in a street-indicator, with the rolls provided with the indicating-ribbon and the gears 11 and 13, of the idler 15, adapted to engage one of said gears, the pivoted plate 17, having the yoke at its end, the gear 21, mounted on said plate, the lever 29, 50 mounted on the pivot of said plate, the ratchet 27, pawl 30, and the eccentric 23, for moving said plate, substantially as described, and for the purpose set forth.

In testimony whereof I have hereunto set 6
my hand this 4th day of October, 1886.

CHARLES H. MILLER.

In presence of—

R. H. SANFORD,
A. M. GASKELL.
